SUCTION CLEANER

Harry B. White, North Canton, Ohio, assignor to
 The Hoover Company, North Canton, Ohio, a
 corporation of Ohio

Application May 25, 1939, Serial No. 275,655

4 Claims. (Cl. 306—13)

The present invention relates to suction cleaners and particularly to new and improved handle control mechanism in a suction cleaner. More specifically the invention relates to a handle control mechanism for rigidly locking the handle in one position with respect to the cleaner casing, and for resistingly controlling the handle in another position with respect to the cleaner casing.

It is an object of the invention to provide a new and improved suction cleaner. It is another object to provide new and improved handle controlling means in a suction cleaner. A further object is to provide means for rigidly locking the handle in one position so that the cleaner may be lifted without relative movement between the handle and the cleaner casing. Another object is to provide means for resistingly maintaining the handle in an operating position, the handle being movable to other positions without manipulation of the handle controlling means. Further objects and advantages of the invention will be apparent upon referring to the following specification and claims and the attached drawings, wherein:

Figure 1 is a side elevational view of a suction cleaner with parts broken away to illustrate one embodiment of the invention;

Figure 2 is an enlarged section along the line 2—2 of Figure 1;

Figure 3 is a side elevational view of the handle locked in storage position;

Figure 4 is a view similar to Figure 3 but showing the handle resistingly held in another operating position, and;

Figure 5 is a perspective view of the handle controlling mechanism.

An embodiment of the invention is disclosed in a suction cleaner comprising a main casing 10 having a nozzle 11 communicating with a passageway 12 extending to a fan chamber 13 provided with an exhaust passageway 14 terminating in a vertical flange 15 to which a dust bag 16 is removably secured. The casing 10 supports a motor housing 17 enclosing an unshown motor having an armature shaft to which a motor pulley 18 is attached for driving an agitator 19 by means of a belt 20. A fan 21 is rotated by the motor to create suction and draw dirt-laden air from the surface being cleaned, through the nozzle 11, suction passageway 12, and fan chamber 13, and discharges the dirt-laden air through the exhaust passageway 14 into the dust bag 16. The cleaner is supported on front and rear wheels 22 and 23 respectively.

The cleaner is propelled over the surface cov-

ering by means of a handle 25 removably disposed in a split socket 26 having a front wall 27, an unshown split rear wall and side walls 28 and 29. The handle socket 26 is pivotally mounted on the cleaner casing 10 by having its side walls 5 rigidly attached to a pivot pin 30 journalled in spaced handle bracket arms 31 upstanding integrally from the cleaner casing 10. Portions 43 of the handle socket side walls 28 and 29 abut the edge 44 of the exhaust flange 15 to limit the downward movement of the handle, and a portion 45 of the handle socket side wall 29 abuts the exhaust flange 15 to limit the upward movement of the handle.

In order to provide pawl means for the handle 15 control, a locking pin 35 and an abutment or pin 36 are mounted on the lower end of the handle socket side wall 29. Each of the pins 35 and 36 is spool-shaped and has opposite end walls 37 provided with inwardly inclined walls 38 merging into a cylindrical portion. The cylindrical portion 40 of the pawl 35 is of considerable less diameter than the cylindrical portion 41 of the pawl 36.

A handle control lever 50 is provided with 25 spaced ears 51 pivotally mounted on a rod 52 supported on members 53 upstanding integrally from the cleaner casing 10 above the exhaust passageway 14. Formed integrally with the control lever 50 is a laterally extending arm 54 provided at its outer end with a foot pedal 55 which is offset with respect to the pivotal axis 52 and extends through an unshown marginal slot in the motor housing 17 above the top wall of the cleaner casing 10.

The segment or detent means are also formed integrally with the control lever 50 and comprises an upstanding arm 56 provided with a V-shaped notch 57 having a lower wall 58 and a shorter upper wall 59. The notch 57 is adapted 40 to separately receive the locking pin 35 and abutment 36 to hold the handle in different operating positions with respect to the cleaner casing 10.

A torsion spring 60 is arranged about the shaft 52 to urge the lever 50 upwardly causing the 45 detent 57 to receive either one of the pawls 35 and 36. The control lever 50 is limited in its clockwise movement by means of a projecting lip 61 abutting the cleaner casing 10 and in its counterclockwise movement by engagement of 50 its lower defining edge 62 with the upper surface of the cleaner casing 10 as viewed in Figure 3.

The weight of the handle is counter-balanced by a spring 63 which has one end secured to a pin 64 rigidly mounted on the handle socket side 55

wall 28, the spring extending through an opening 65 in the casing wall 10 and having its opposite end attached to a member 66 rigidly mounted on the cleaner exhaust flange 15.

5 In operation, assume that the handle is in storage position as shown in Figure 3 the pawl 35 being disposed in the recess 57. The handle is rigidly locked in this position with respect to the cleaner casing due to the relative greater 10 size of the recess 57 with respect to the small diameter 40 of the pawl 35. In order to lower the handle to a lower operating range, the operator depresses the foot pedal 55 against the force exerted by the torsion spring 60 causing the segment means 57 to move out of engagement with the pawl 35, and thereafter the operator removes his foot from the pedal 55. Downward movement 15 of the handle is limited by engagement of the pawl 36 in the recess 57 and the handle is resitstingly held in this position as shown in Figure 20 4. Should the operator desire to move the handle to a lower position a downward force is exerted on the handle and since the diameter 41 of the pawl 36 is relatively larger than the recess 57 25 the pawl 36 will move along the upper wall 59 of the slot 57 and pivot the control lever 58 counter-clockwise as viewed in Figure 4 until the pawl 36 is free of the slot 57. The handle may now be moved freely downwardly until the portions 43 of the handle socket side walls abut the 30 exhaust flange 15.

In order to move the handle from a low to a high operating position the operator merely moves the handle upwardly and the pawls 35 and 36 35 slide on the upper surface 70 of the segment means and thence along the lower defining wall 58 of the recess 57 without the necessity of manipulating the foot lever 55.

From the foregoing it will be perceived that I 40 have provided a handle control mechanism wherein the handle is locked rigidly in one position with respect to the cleaner casing, that means have been provided for resistingly locking the handle at the normal operating position as viewed 45 in Figure 4, and that the latching means include detent means comprising a single recess 57 which separately receives the pawl means to hold the handle in adjusted positions. The handle is free to move unrestricted throughout the ranges defined 50 between the pawls 35 and 36, and between the latter and the lowest handle position.

It is to be understood that the protection herein applied for is not confined to the particular combinations of features or elements set out in the 55 following claims. Protection is herein applied for, for any one or more of the features or elements referred to in the following claims, or described in the foregoing specification or shown in the accompanying drawings, either independently or in combination.

I claim:

1. A handle-positioning mechanism comprising a body, a handle pivoted on said body, cooperating handle-positioning means including spaced abut-

ment elements of differing contours carried by said handle and a spring-pressed manually operable seat carried by said body and adapted to receive selectively said elements, characterized in that one of said elements lockingly seats within 5 said seat necessitating manual operation of said seat for disengagement while a second element resistingly seats in said seat being displaceable therefrom by a force exerted through the handle.

2. A handle-positioning mechanism comprising 10 a body, a handle pivoted on said body, and cooperating handle-positioning means including relatively movable abutment elements and a seat mounted on said relatively movable handle and body, said abutment elements being spaced circumferentially relative to the pivotal axis of said handle and of differing contours, said seat being spring-pressed and adapted to receive selectively 15 said elements upon the pivotal movement of said handle, a first element seating lockingly within 20 said seat requiring manual displacement to effect separation and a second element resistingly seating in said seat, and manually operable means to effect separation of said first element and said seat. 25

3. In an ambulatory machine having a body, a handle pivoted on said body, a locking pin and abutment mounted on said handle, detent means mounted on said body and including a single recess for separately receiving said pin and abutment, manually operated means for controlling 30 said detent means to selectively engage said pin and abutment for holding said handle in different adjusted positions, said recess being of such size with respect to said locking pin as to retain the latter therein to rigidly lock said handle with respect to said body, said recess being of such size with respect to said abutment as to engage the latter to resistingly maintain said handle in adjusted position, and to cause escape of said engagement upon positive force being exerted on 35 said handle whereby the latter is free to move with respect to said body.

4. A handle positioning mechanism comprising, 40 a body, a handle pivoted on said body, cooperating handle positioning means on said handle and body and including large and small diameter pins and recessed means, said pins being selectively disposed in said recessed means upon movement of said handle to different positions with respect 45 to said body, the larger pin being of such diameter with respect to the area of said recessed means as to be retained in the latter to resistingly hold said handle in adjusted position but movable to another position by exerting a positive force on 50 said handle, the smaller pin being of such diameter with respect to the area of said recessed means as to be retained in the latter to lock said handle in position against any force exerted on said handle, and means for moving said recessed 55 means out of engagement with said smaller diameter pin whereby said handle may be moved to another position. 60

HARRY B. WHITE.
